(57) **CLAIM**

The ornamental design for an electric muscle stimulator, as shown and described.

DESCRIPTION

FIG. 1 is a top plan view of an electric muscle stimulator showing the new design;

FIG. 2 is a bottom plan view thereof;

FIG. 3 is a top perspective view thereof;

FIG. 4 is a bottom perspective view thereof;

FIG. 5 is a rear side elevational view thereof;

FIG. 6 is a front side elevational view thereof;

FIG. 7 is a right side elevational view thereof, with the left side being a mirror image; and,

FIG. 8 is a perspective environmental view thereof.

In the drawings, the broken lines depict environmental subject matter only and form no part of the claimed design.
